CORE CLAMP

Hirsch Epstein, Chicago, Ill., assignor, by direct and mesne assignments, to Advance Transformer Co., Chicago, Ill., a corporation of Illinois

Original application December 11, 1944, Serial No. 567,542. Divided and this application October 1, 1945, Serial No. 619,512

1 Claim. (Cl. 175—356)

1

This application is a division of my pending application, Serial No. 567,542, filed December 11, 1944.

The present invention relates to transformers or reactors, particularly such as are used in connection with alternating current hot cathode fluorescent lighting devices.

It is one of the objects of the present invention to provide a transformer or reactor for the above mentioned purposes which will be silent in operation.

The core of transformers of the type here involved consists of two stacks of laminations, preferably but not necessarily E-shaped, which are placed in abutment to make an almost closed, but not completely closed, magnetic circuit, a small magnetic gap or space being left between the two cores. Generally the two core parts are fitted into one or more coils, which are the coils of the transformer or reactor. In order to obtain proper electrical functioning of a structure of this type it is necessary that the air gap be of a constant value. A piece of non-magnetic material, such as paper or the like, is positioned between the two core structures to maintain the necessary minimum spacing between them. It has been found that there is a tendency for the two core structures to separate from one another and thus increase the air gap between them, unless means is provided to prevent such separation. It is one of the objects of the present invention to provide a simple clamp structure for holding the two core parts together against separation.

I have found that the end laminations of a core of the above mentioned type are primarily responsible for the objectionable transformer noises. It is one of the objects of the present invention to provide a simple type of clamp for holding the outermost laminations against vibration.

It is a still further object of the present invention to provide a simple clamp which will perform the function of preventing vibration of the end laminations and also perform the function of preventing separation of the two core structures.

The attainment of the above and further objects of the present invention will be apparent from the following specification taken in conjunction with the accompanying drawing forming a part thereof.

In the drawing:

Figure 1 is a top view of a reactor embodying the present invention, parts of the reactor being broken away to illustrate the interior construction;

2

Figure 2 is a view taken along the line 2—2 of Figure 1 and looking in the direction of the arrows; and

Figure 3 is a view taken along the line 3—3 of Figure 1 and looking in the direction of the arrows.

In the drawing I have shown the principles of the present invention as applied to a reactor such as used in alternating current fluorescent lighting circuits. This reactor comprises a single coil **c** wound on a spool **1** of paper, cardboard or the like, and in which is assembled a core consisting of two identical stacks **2—3** of thin, E-shaped, silicon steel laminations.

15 Each lamination includes an end portion **4** from which project outer legs **5** and **6** and a central leg **7**. The stacks **2—3** of laminations are assembled in a manner such that there is slight gap **8** between the central legs **7** of the two stacks **20** and a corresponding gap **9** between the legs **5—5** and between the legs **6—6**. These gaps may be filled by thin paper spacers. A wooden wedge **10** is forced through the core between the legs **7** and the tube **10** to hold the coil tightly on the cores.

25 In order to hold the two stacks of laminations against vibrating towards and from one another when a 25 cycle or 60 cycle current flows through the coil there is provided a pair of identical clamps **13—14** on opposite sides of the reactor. Each clamp is, optionally, spaced from the core by a sheet of paper **16**. The clamps are made of soft steel or iron which is dead, that is, substantially devoid of springiness. The clamps are 30 placed on the reactors and then the arms **18—18** of the clamps are pressed together as by means of a pneumatic or hand press. Each clamp **13—14** may, if desired, have a pair of ears **20** constituting clamping jaws on opposite sides thereon, 35 of which ears fold down and embrace the free ends of adjacent outer legs **5** or **6** as the case may be. These ears are preferably, although not necessarily, separated from the core structure by the paper sheet **16**. The ears **20—20** of each 40 clamp are pressed together in firm pressure engagement with the reactor by the exertion of a great pressure thereon in a pneumatic or hand press. The clamps **13—14** not only prevent vibration of the adjacent free ends of the legs **5—5** and **6—6** but also prevent the core structures **2—3** from rocking or vibrating towards and from one another under the magnetic action to which the structure is subjected.

45 The assembled reactor is varnished with an insulating varnish and placed in a casing and 50

55

completely encased by an insulating compound, such as tar, within the casing, as is usual in the art.

I have found that as a result of the clamping arrangement herein disclosed the magnetic structures are exceedingly quiet in their action where otherwise they would be quite noisy. The clamps are simple and economical of construction and easily positioned on the magnetic structure.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

In an alternating current magnetic apparatus, a magnetic core comprising two separate stacks of assembled laminations together forming a central leg and two outer legs joined by end portions, there being a non-magnetic gap between the two stacks at the middle of the outer legs of the assembly, means surrounding the central leg for setting up an alternating magnetic flux in said core, each outer leg having a clamp of metal that is substantially devoid of springiness, each clamp including a clamp body extending across the stacks of laminations and lengthwise of an outer leg of the core, each clamp body having at opposite ends thereof arms pressing the two stacks of laminations towards one another and said lengthwise extending clamp body having clamping jaws at the opposite longitudinal

edges thereof and at the non-magnetic gaps of the core, said jaws being bent from the clamp body to a position extending over one of the non-magnetic gaps between the stacks and overlying the portions of the outer laminations adjacent the non-magnetic gap and firmly clamping said portions of the laminations together thereby holding said portions against vibration, each jaw being of substantially greater width along its line of bend from the clamp body than it is at the pressure engaging jaw end remote from the clamp body, the maximum length of each jaw in a direction lengthwise of the member over which it extends being substantially less than the minimum distance from the jaw to an adjacent arm of the clamp.
